UNITED STATES PATENT OFFICE.

WALTER A. FRANCK, OF LOUISVILLE, KENTUCKY.

DESIGN FOR A CIGAR-CUTTER.

55,509.

Specification for Design. Patented June 22, 1920.

Application filed December 26, 1919. Serial No. 347,600. Term of patent 14 years.

To all whom it may concern:

Be it known that I, WALTER A. FRANCK, a citizen of the United States, residing at Louisville, in the county of Jefferson and State of Kentucky, have invented a new, original, and ornamental Design for Cigar-Cutters, of which the following is a specification, reference being had to the accompanying drawing, forming a part thereof.

The figure is a perspective view of a cigar cutter, showing my new design.

I claim:

The ornamental design for a cigar cutter as shown.

WALTER A. FRANCK.
